LYMAN BARUCH POPE, OF HAVERHILL, MASSACHUSETTS, ASSIGNOR TO POPE MACHINERY CORPORATION, OF HAVERHILL, MASSACHUSETTS, A CORPORATION OF MASSACHUSETTS

HEEL-SHANK-SHAPING MACHINE

Application filed June 9, 1928. Serial No. 284,032.

This invention relates to the finishing of Louis and similar heels and particularly to the shaping of the shank portion of such a heel or that which extends forward from the breast of the heel toward or along the shank of the shoe.

It is the object of the present invention to provide a machine of this general type which is adapted to impart a better finish to the heel and which is capable of far greater production capacity than has been possible with machines of this type heretofore.

Before explaining in detail the present invention, and the method or mode of operation embodied therein, it is to be understood that the invention is not limited in its application to the details of construction and arrangement of parts illustrated in the accompanying drawings, since the invention is capable of other embodiments and of being practised or carried out in various ways. Also it is to be understood that the phraseology or terminology employed herein is for the purpose of description and not of limitation, and it is not intended to limit the invention beyond the terms of the several claims hereto appended or the requirements of the prior art.

The invention will be more clearly understood from the following description in conjunction with the accompanying drawings; in which,

Fig. 1 is a front elevation, partly in section, of a machine embodying the invention;

Fig. 2 is a plan view of the same;

Fig. 3 is a similar view showing the work engaging the shaping tool;

Fig. 4 is an enlarged side elevation of the work carrier and associated parts;

Fig. 5 is a plan view thereof looking in the direction of the arrow in Fig. 4;

Fig. 6 is a section taken on the line 6—6 of Fig. 4;

Fig. 7 is an end elevation as viewed from the right of Fig. 1;

Fig. 8 is a similar view showing the relation of the parts when the work has been clamped in position previous to the shaping operation;

Fig. 9 is a section taken on the line 9—9 of Fig. 4;

Fig. 10 is a section taken on the line 10—10 of Fig. 1;

Fig. 11 is a diagram showing successive positions of the work as it moves past the shaping tool;

Fig. 12 is a diagram showing the relation of the work and shaping tool;

Figs. 13 and 14 are a vertical section and front elevation respectively of a heel blank.

While, as will hereinafter appear, the machine of the invention is adapted for use in connection with heels of a wide variety of forms, a typical heel of the type to which the invention is applicable is shown at A in Figs. 13 and 14. Said heel in its finished form is provided with a concave upper surface *a* adapted to engage and fit the heel seat of the shoe, a suitably shaped back or body portion *d*, a breast portion *b* and a shank *c* which projects forwardly from the breast. In the finished heel the shank *c* joins the breast *b* and merges therewith in a smooth curve as shown in Fig. 13, said shank being also transversely curved in accordance with the transverse curvature of the heel seat engaging portion *a* as most clearly shown in Fig. 14. The heel seat engaging portion *a*, breast *b* and back *d* are formed prior to the transverse shaping of the shank *c* by instrumentalities which constitute no part of the present invention. The heel blank after the operation of said instrumentalities has a shank of the shape indicated by dotted lines in Figs. 13 and 14, the underside thereof adjacent the breast *b* being transversely straight as the result of the formation of said breast *b*, which gives said shank its proper vertical curvature but leaves, particularly at the sides of the shank, a quantity of surplus material *e* which is subsequently removed to finish the shank. The present invention is directed to the subsequent shaping or finishing of the shank *c*, by removing this surplus material *e*, to give said shank its proper transverse curvature in parallelism to the heel seat engaging portion *a*.

In the machine illustrated a shaping tool or cutter B is suitably mounted on the end of

a shaft 15 provided with a pulley 16 by which power may be applied from any suitable source through a belt 17. The shaft 15 is suitably journaled in a head 18 on a table 19. The heel blank A is supported in a work carrier, hereinafter described, mounted on a shaft 20, said shaft being journaled in suitable bearings in a mounting on the table 19 and rotated by suitable mechanism, hereinafter described, to swing the heel blank A past the tool B. The mounting for the shaft 20 comprises a support or carriage 21 adjustable in the direction of the axis of the shaft 20 by a manually operated adjusting screw 22 in a guide on a second carriage 23. The carriage 23 is adjustable in a direction transverse to the axis of the shaft 20 by a manually operated adjusting screw 24 in a guide 25 secured to the table 19 by a clamp comprising a threaded stem 26 extending through an enlarged opening (not shown) in the table and provided on the underside of the latter with a threaded hand operated nut 27.

In accordance with the invention a jack 30 is mounted upon the shaft 20 to rotate therewith and may comprise a U-shaped member having upwardly extending arms 31 adapted to engage grooves 32 near the end of the shaft 20. The jack is provided with an adjusting screw 33 passing through a threaded opening 34 in the jack and into an opening 35 near the end of the shaft 20. A key, such as a set screw 36, extends into the opening 34 so as to engage an annular groove 37 near the end of the adjusting screw 33 thereby preventing relative movement between the adjusting screw 33 and the shaft 20 and permitting adjustment of the jack 30. The legs 31 are provided at the upper ends with a clamping bolt 40 thereby permitting the legs to be pressed snugly into engagement with the bottom of the slots 32 in the shaft 20.

A work carrier 45 is provided with a tail 46 adapted to fit between lugs 38 at the upper end of the jack 30 and having an opening 47 therein serving as a bearing for a pivot bolt 48 passing through said lugs. A nut 49 is provided at one end of the bolt 48 so as to engage the outer surface of one of the lugs 38 and draw said lugs snugly into engagement with the tail 46 thereby permitting the work carrier 45 to be located in any desired angular position relative to a plane perpendicular to the axis of the shaft 20. The carrier 45 is provided with depending lugs 41 which are pivotally connected with an arm 42 extending between lugs 43 projecting from the jack 30. The arm 42 is provided with a slot 44 to receive a clamping bolt 28 extending between the lugs 43.

A heel shank support or template 50 having an upper curved surface corresponding to the curvature of the heel seat is adjustably

mounted upon the carrier 45 and for this purpose is provided with a depending arm 39 passing downwardly through an opening 51 (Fig. 9) in the tail 46 of the work carrier and held in any desired adjusted position therein as by a set screw 52. The heel blank A may be clamped in position upon the work carrier 45 with the shank engaging the support 50 by a stationary clamp 54 adapted to engage one side of the heel and a movable clamp 55 adapted to engage the other side of the heel. The stationary clamp 54 may be provided with a longitudinal slot 56 to permit the passage therethrough of a thumb screw 57 adapted to engage either of the openings 58 in the work carrier 45.

The movable clamp 55 may be secured by screws 16 to one end of a lever L pivoted at an intermediate point to an adjustable slide 60 as by a pivot bolt 61 passing through a bushing 62 in an opening in said lever and engaging the slide 60 (see particularly Fig. 6). The bushing 62 may be provided with an enlarged portion 63 interposed between the lever L and slide 60 and extending through an elongated slot 12 in the work carrier, said portion 63 serving as a bearing supporting the lever in spaced relation to the work carrier 45. The slide 60 is adjustably mounted in ways 65 in the work carrier and may be moved to any desired position therein by an adjusting screw 66 swivelled in a cross member 67 extending between the ways 65. The slide 60 may be clamped in the desired adjusted position by a bolt 68 passing through a slot 69 in the slide and engaging the work carrier. In this manner the position of the pivot bolt 61 of the movable clamp may be adjusted for use in connection with heels of a variety of different sizes to bring the pivot bolt to a point such that the force exerted by the movable clamp 55 of the lever L acts substantially in the direction of the stationary clamp 54 thereby preventing any tendency of the heel blank to shift.

The other end 71 of the lever L is provided with a yoke 72 adapted to receive one end of an arm 73 which may be clamped in any desired angular position relative thereto by a clamp, such as a bolt 75, passing through the yoke 72 and arm 73 and a nut 76 adapted to engage the outer surface of one arm of the yoke and press the same snugly against the arm 73. The other end of the arm 73 is adjustably secured to a yoke 78 as by a bolt 79 and nut 80. A cam follower 82, such as a roll, is suitably mounted upon the yoke 78 and is adapted to engage cams 83 and 84 adjustably mounted upon a bracket 85 extending from and secured to the carriage 21, as by bolts 86 passing through slots 87 in the bracket and engaging the carriage. The cams 83 and 84 are provided on their lower surface with guideways 88 adapted to engage ways 89 upon the bracket 85. The po-

sition of the cams 83 and 84 may be varied by adjusting screws 90 and 91 swivelled in arms 92 and 93 extending upwardly from the bracket 85 and engaging the respective cams.

5 The cams 83 and 84 may be held in adjusted position by bolts 94 and 95 passing through slots 96 and 97 in the cams 83 and 84 respectively. The cam follower 82 is held in contact with either of the cams by a spring 130 10 extending between the free ends of arms 131 and 132 extending from the lever L and the carrier 45 respectively.

In accordance with the invention, the shaft 20 is rotated continuously in one direction 15 to move the heel blank A past the shaping tool B. For this purpose the carriage 21 is provided with a support 100 having a housing 101, said support being secured to a portion 102 extending upwardly from the carriage. A motor 103 is suitably mounted upon the support 100 and is provided with an armature shaft 104 carrying a pinion 105 20 engaging a gear 106 mounted upon a shaft 107 supported for rotation in suitable bearings 108 in the housing 101. A pinion 14 is mounted upon the shaft 107 and is adapted to engage a gear 111 mounted upon an axially movable shaft 112 supported for rotation in suitable bearings 113 in member 102. The shaft 112 is provided with a head 115 normally held in spaced relation to the member 102 by a spacer 116 pivotally mounted upon a stud 118 (Fig. 10) projecting from the member 102 and provided with a slot 117 35 adapted to receive the shaft 112. The shaft 112 is provided with a pinion 120 adapted to mesh with a gear 121 mounted upon the shaft 20.

A suitable breast gage 125 for positioning the heel blank A upon the work carrier 45 is 40 adjustably secured upon a bracket 126 as by a thumb screw 127 passing through a slot 128 in said gage and engaging the bracket 126. The bracket 126 is adjustably mounted upon 45 the carriage 21 as by a thumb screw 181 passing through a slot 129 in the bracket 126 and engaging the carriage 21. In order to permit movement of the heel blank A toward the shaping tool B without being obstructed by 50 the breast gage 125, the latter is curved in the direction of movement of the work. The positioning of the blank during the rotation of the carrier with the breast of the heel at right angles to its axis assists in preventing its obstruction by the breast gage. The curvature of the breast gage also permits the insertion of the heel blank during a considerable range of movement of the carrier.

In operation the carriages 21 and 23 are 60 moved to suitable positions with respect to the shaping tool B by manipulation of the adjusting screws 22 and 24. The spacer 116 is turned out of engagement with the head 115 of the shaft 112 to permit said shaft to be moved axially and move the pinion 120

out of mesh with the gear 121, thereby disconnecting the driving connections between the motor 103 and the shaft 20. The clamping bolt 40 is loosened to permit adjustment of the jack 30 by the adjusting screw 33, the jack then being held in adjusted position by tightening the clamping bolt 40. The work carrier 45 is then adjusted angularly with respect to a plane perpendicular to the shaft 20 to bring the breast of the heel at right angles to its axis of rotation. This is accomplished by loosening the nut 49 and clamp 28, permitting movement of the work carrier 45 to the desired position. The nut 49 and clamp 28 are then tightened to clamp the work carrier in its adjusted position. The breast gage is then brought to the desired position to locate properly the position of the breast of the heel upon the work carrier by adjusting the bracket 126 vertically and the breast gage 125 horizontally.

When these adjustments have been made, the shaft 112 is moved axially to bring the pinion 120 into engagement with the gear 121 and the spacer 116 is then moved to its normal position between the head 115 and the member 102 of the carriage 21. The shaft 20 is then connected for continuous rotation in one direction. During this rotation the cam follower 82 is held in contact successively 95 with the cams 83 and 84 which control the lever L and clamp 55 to move said clamp automatically to receive, clamp against and permit discharge of the work. Thus, when the carrier 45 is in work receiving position as shown in Figs. 1, 2 and 7 the follower 82 engages the surface α of the cam 83 which holds the clamp 55 apart from the clamp 54 sufficiently to permit the insertion of the work. Upon further rotation of the shaft 20 the follower 82 passes off the surface α as shown 100 in Fig. 8 and permits the spring 130 to move the clamp 55 into engagement with the work. The work is released by engagement of the follower 82 with the surface Z of the cam 84. 105

By this arrangement the quality of the work is greatly improved and the production of each machine is greatly increased. The merging of the shank curvature with the breast is improved markedly by holding the breast during the shaping operation at right angles to the axis of rotation of the heel. And the work passing the cutter at a definite speed or feed prevents chipping or breaking the work.

I claim:

1. In a heel shank shaping machine, in combination, a shaping tool, a rotatably mounted shaft, a work carrier mounted on said shaft to rotate therewith, means for rotating said shaft to move the heel past said tool, means for clamping a heel upon said carrier, and means permitting the adjustment of the position of said heel to bring its breast at right angles to its axis of rotation.

2. In a heel shank shaping machine, in combination, a shaping tool, a rotatably mounted shaft, a work carrier mounted on said shaft to rotate therewith, means for clamping the work upon said carrier, means for rotating said shaft to move said heel past said tool, and means permitting the adjustment of the position of said carrier angularly to bring the breast of said heel at right angles to its axis of rotation.
3. In a heel shank shaping machine, in combination, a shaping tool, a rotatably mounted shaft, a work carrier mounted on said shaft to rotate therewith, means for rotating said shaft to move the heel past said tool, means for clamping a heel upon said carrier, means permitting the adjustment of the position of said heel to bring its breast at right angles to its axis of rotation, and an adjustable heel shank support.
4. In a heel shank shaping machine, in combination, a shaping tool, a carriage, a shaft rotatably mounted in said carriage, a work carrier mounted to move with said shaft, means for clamping the work upon the carrier, means for rotating said shaft to move the work past said tool, a breast gage mounted on said carriage, and an adjustable heel shank support.
5. In a heel shank shaping machine, in combination, a shaping tool, a rotatably mounted shaft, a work carrier mounted to move with said shaft, a movable work clamp on said carrier, means for rotating said shaft continuously in one direction to move the work past said tool, and cams arranged to control said movable clamp during the movement of said carrier to receive and discharge the work.
6. In a heel shank shaping machine, in combination, a shaping tool, a rotatably mounted shaft, a work carrier mounted to move with said shaft, a movable work clamp on said carrier, means for rotating said shaft continuously in one direction to move the work past said tool, and cams arranged to control said movable clamp during the movement of said carrier to receive and discharge the work, and a breast gage curved in the direction of movement of said work.
7. In a heel shank shaping machine, in combination, a shaping tool, a carriage, a shaft rotatably mounted in said carriage, a work carrier mounted to move with said shaft, means for clamping a heel upon said carrier, a breast gage mounted on said carriage, means for adjusting the position of said carriage, a motor, and driving connections between said motor and shaft for rotating the latter continuously in one direction to move the heel past said tool, said gage being constructed to permit the shank of said heel to clear said gage as said shaft is rotated and means permitting the disconnecting of the motor and shaft.
8. In a heel shank shaping machine, in combination, a carriage, a shaping tool, a shaft rotatably mounted in said carriage, a work carrier mounted to move with said shaft, a breast gage, means permitting adjustment of the position of said work relative to said shaping tool, means for rotating said shaft to move the work past said tool, a stationary work clamp, a movable work clamp and means for adjusting the position of said movable clamp to act upon said heel in the direction of the stationary clamp.
9. In a heel shank shaping machine, in combination, a carriage, a shaping tool, a shaft rotatably mounted in said carriage, a work carrier mounted to move with said shaft, means for clamping the work upon said carrier, means for adjusting the position of said carriage, driving mechanism for rotating said shaft continuously in one direction including a train of gears one of which is movable axially, and removable means preventing axial movement of said gear.
10. In a heel shank shaping machine, in combination, a shaping tool, a rotatably mounted shaft, a work carrier mounted to move with said shaft, a slide on said carrier, means for clamping the work upon said carrier including a stationary and a movable clamp, said movable clamp comprising a lever pivotally mounted upon said slide so as to permit engagement of one end with the work, and means for adjusting said slide so that said lever may act upon the work in the direction of the stationary clamp.
11. In a heel shank shaping machine, in combination, a shaping tool, a rotatably mounted shaft, a work carrier mounted to move with said shaft, means for clamping a heel upon said carrier including a stationary and a movable clamp, said movable clamp comprising a lever pivotally mounted at an intermediate point and arranged to permit engagement of one end with said heel, means permitting adjustment of the position of said carrier angularly to bring the breast of said heel at right angles to its axis of rotation, a cam follower adjustably mounted at the other end of said lever, a cam means for maintaining engagement between said cam and follower, and means for rotating said shaft to move said heel past said tool.
12. In a heel shank shaping machine, in combination, a shaping tool, a rotatably mounted shaft, a work carrier mounted to move with said shaft, means for clamping a heel upon said carrier including a stationary and a movable clamp, said movable clamp comprising a lever pivotally mounted at an intermediate point and arranged to permit engagement of one end with said heel, means permitting adjustment of the position of said carrier angularly to bring the breast of said heel at right angles to its axis of rotation, a cam follower adjustably mounted at the other end of said lever, a cam means for maintaining engagement between said cam and follower, and means for rotating said shaft to move said heel past said tool.

- other end of said lever, an adjustable cam, means for maintaining engagement between said cam and follower, and means for rotating said shaft to move said heel past said tool.
13. In a heel shank shaping machine, in combination, a shaping tool, a rotatably mounted shaft, a work carrier mounted to move with said shaft, means for clamping a heel upon said carrier including a stationary and a movable clamp, said movable clamp comprising a lever pivotally mounted at an intermediate point and arranged to permit engagement of one end with said heel, means permitting adjustment of the position of said carrier angularly to bring the breast of said heel at right angles to its axis of rotation, a cam follower adjustably mounted at the other end of said lever, a cam, means for maintaining engagement between said cam and follower, means for rotating said shaft continuously in one direction to move said work past said tool, and a breast gage curved in the direction of movement of the work.
14. In a shank shaping machine, in combination, a shaping tool, a rotatably mounted shaft, a work carrier mounted to move with said shaft, a slide on said carrier, means for clamping a heel upon said carrier including a stationary and movable clamp, said movable clamp comprising a lever pivotally mounted upon said slide so as to permit engagement of one end with said heel, means for adjusting said slide so that said lever may act upon said heel in the direction of the stationary clamp, means for rotating said shaft to move said heel past said tool, means permitting angular adjustment of the position of said carrier to bring the breast of said heel at right angles to its axis of rotation, a cam follower adjustably mounted at the other end of said lever, a cam, and means for maintaining engagement between said cam and follower.
15. In a shank shaping machine, in combination, a shaping tool, a carriage, a shaft rotatably mounted in said carriage, a work carrier mounted to move with said shaft, a slide on said carrier, means for clamping a heel upon said carrier including a stationary and movable clamp, said movable clamp comprising a lever pivotally mounted upon said slide so as to permit engagement of one end with said heel, means for adjusting said slide so that said lever may act upon said heel in the direction of the stationary clamp, means for rotating said shaft to move said heel past said tool, and a heel shank support adjustably mounted upon said carrier.
- In testimony whereof I affix my signature.
- LYMAN BARUCH POPE.

115

work past said tool, and a breast gage curved in the direction of movement of said work.

16. In a heel shank shaping machine, in combination, a shaping tool, a carriage, a shaft rotatably mounted in said carriage, a work carrier mounted to move with said shaft, a slide on said carrier, and means for clamping a heel upon said carrier including a stationary and movable clamp, said movable clamp comprising a lever pivotally mounted upon said slide so as to permit engagement of one end with said heel, means for adjusting said slide so that said lever may act upon said heel in the direction of the stationary clamp, driving mechanism for rotating said shaft including a train of gears one of which is movable axially, detachable means preventing axial movement of said gear, and a breast gage mounted on said carriage and curved in the direction of movement of said work.

17. In a shank shaping machine, in combination, a shaping tool, a carriage, a shaft rotatably mounted in said carriage, a work carrier mounted to move with said shaft, a slide on said carrier, and means for clamping a heel upon said carrier including a stationary and movable clamp, said movable clamp comprising a lever pivotally mounted upon said slide so as to permit engagement of one end with said heel, means for adjusting said slide so that said lever may act upon said heel in the direction of the stationary clamp, means permitting angular adjustment of the position of said carrier to bring the breast of said heel at right angles to its axis of rotation, a cam follower adjustably mounted at the other end of said lever, a cam, means for maintaining engagement between said cam and follower, driving mechanism for rotating said shaft including a train of gears one of which is movable axially, detachable means preventing axial movement of said gear, a breast gage mounted on said carriage and curved in the direction of movement of the work, and a heel shank support adjustably mounted upon said carrier.
